UNITED STATES PATENT OFFICE.

JOHN FRANCIS BENNETT, OF PITTSBURG, PENNSYLVANIA.

STRAIGHT WATER-PIPE.

SPECIFICATION forming part of Letters Patent No. 298,657, dated May 13, 1884.

Application filed September 24, 1883. (No model.)

To all whom it may concern:

Be it known that I, JOHN FRANCIS BENNETT, of Pittsburg, in the county of Allegheny and State of Pennsylvania, have invented certain new and useful Improvements in Straight Pipes; and I do hereby declare that the following is a full, clear, and exact description thereof, reference being had to the accompanying drawings, and to the letters of reference 10 marked thereon, which form part of this specification.

My invention relates to improvements in straight pipes in which the ends are of slightly increased area over the body of the pipe; and 15 the objects of my improvements are, first, to reduce the obstruction of the fluid passing through the pipe to a minimum, and, second, to necessitate, therefore, less power or pressure to force the liquid through the pipe than heretofore requisite. I attain these objects by the 20 pipe illustrated in the accompanying drawings, in which—

Figure 1 represents a vertical broken section of the pipe constructed according to the 25 principles of my invention. Fig. 2 is an end view of the same, and Fig. 3 is a broken elevation of the same.

In the conveyance of water and other incompressible liquids desired to be furnished 30 for use at a given pressure, an initial pressure equal frequently to double the desired pressure must be imparted in order to attain the end sought. In all cases there is such a loss of velocity, momentum, or pressure that almost invariably additional power has to be applied to 35 give the water a sufficient impulse to reach the point of delivering, although the source may be of such altitude or pressure that under theoretical conditions the water should have over and 40 above the requisite pressure without the use of intermediate power. The mechanical conditions producing this loss are capable of partial remedy. Friction between the surfaces cannot and should not entirely be dispensed

with; but there should be such a diminution 45 in its hurtful effects that its conveyance shall be more economically secured. Especially does this reasoning apply to water transmitted for purposes of power where any decrease in its pressure correspondingly impairs its 50 value as a motor. What has been said as to water applies in different degrees to the transmission of steam, gas, compressed air, and other fluids. It will therefore be understood that this pipe is efficacious in their conveyance as well; hence I have, by experiment and careful study of the laws of moving fluids, devised a pipe capable of accomplishing all the 55 purposes pointed out above.

I construct the pipe so that the area at the 60 entrance and exit ends shall be about twice that of the main body, making the frustum of cone forming the entrances of a length equal to about two diameters of the main body of the pipe. I generally shape the ends conically, 65 rounded, or bell-mouthed.

I do not restrict myself to the specific dimensions herein named, as exigencies may necessitate slight modifications, so long as the 70 features of my invention herein described are observed.

Having thus fully described my invention, what I claim, and desire to secure by Letters Patent of the United States, is—

A straight pipe having bell-mouthed-shaped 75 ends which have, respectively, an area equal to twice that of the main body, the length of frustum of cone forming the entrances being equal to two diameters of the main body of the pipe, for the purpose herein fully set forth. 80

In testimony that I claim the foregoing as my own I affix my signature in presence of two witnesses.

JOHN F. BENNETT.

Witnesses:

M. E. HARRISON,
ALEX. RANDOL.
